UNITED STATES PATENT OFFICE.

PHILIP C. EMANUEL, OF BENNETTSVILLE, SOUTH CAROLINA.

DEVICE FOR PULLING PUMP-PIPES.

988,761.

Specification of Letters Patent.

Patented Apr. 4, 1911.

Application filed May 31, 1910. Serial No. 564,207.

To all whom it may concern:

Be it known that I, PHILIP C. EMANUEL, a citizen of the United States, residing at Bennettsville, in the county of Marlboro 5 and State of South Carolina, have invented a new and useful Device for Pulling Pump-Pipes, of which the following is a specification.

The invention relates to a device for pulling pump pipes.

The object of the present invention is to provide a simple, inexpensive and efficient device of great strength and durability, designed for pulling out of the ground driven 15 pump pipes when it becomes necessary to remove the same for renewing the point or screen, or for any other purpose, and adapted to be operated by hand at the surface of the ground, and capable of enabling a pump 20 pipe to be easily removed in sections without liability of crushing or otherwise damaging the pump pipe.

With these and other objects in view, the invention consists in the construction and 25 novel combination of parts hereinafter fully described, illustrated in the accompanying drawing, and pointed out in the claims here-to appended; it being understood that various changes in the form, proportion, size 30 and minor details of construction, within the scope of the claims, may be resorted to without departing from the spirit or sacrificing any of the advantages of the invention.

35 In the drawing:—Figure 1 is a vertical sectional view, partly in elevation, of a pump pipe pulling device, constructed in accordance with this invention. Fig. 2 is a transverse sectional view of the upper portion of the device. Fig. 3 is a horizontal sectional view of the same. Fig. 4 is a reverse plan view of a portion of the operating lever. Fig. 5 is a detail sectional view, illustrating the manner of mounting the 40 dogs or catches. Fig. 6 is a detail perspective view of an extension section of the tubular shield.

Like numerals of reference designate corresponding parts in all the figures of the 50 drawing.

In the embodiment of the invention illustrated in the accompanying drawing, 1 designates a tubular shield, surrounding the upper portion of the pump pipe 2, and 55 equipped at opposite sides with laterally projecting lugs 3, arranged in pairs and

adapted to be engaged by dogs or catches 4, carried by a cross head 5, which is operated by a lever 6. The tubular shield, which surrounds the pump pipe, is adapted to prevent the same from being crushed or otherwise damaged in pulling the same from the ground, and it is provided at its upper end with exterior screw threads 7, engaging interior screw threads 8 of a cap 9. The cap 60 9, which is fitted on the upper end of the pump pipe, is provided with a socket 10 to receive the upper end of the tubular shield, and it is also provided with a threaded upper counter-bore 11 to engage the 65 threaded upper end 12 of the top section of the pump pipe. Instead, however, of providing a threaded connection between the upper end of the tubular shield and the cap, these parts may be detachably connected in 70 75 any other preferred manner. The cap is readily uncoupled from the tubular shield and disconnected from the pump pipe to enable the parts to be removed after a section of the pump pipe has been pulled out 80 of the ground, as hereinafter more fully explained. The pump pipe is pulled from the ground in sections, and as soon as one section thereof is clear of the ground, it is uncoupled and the device is connected with 85 the next section of the pump pipe.

The lugs 3 are beveled at their outer edges and are shouldered at their lower edges, and the opposite catches 4 engage the lower edges of the lugs when the lifting 90 arm or portion of the lever is raised, and are adapted to slide over the lugs when the lifting portion of the lever is lowered to engage the catches with another set of lugs.

The cross head 5 is composed of a pair of 95 metallic bars 13, spaced apart by metallic blocks or pieces 14, interposed between the end portions of the bars 13, which are provided with oppositely bowed intermediate portions 15, forming an opening to receive 100 the shield. The end portions of the bars 13 are preferably straight and are bolted, or otherwise secured to the blocks or pieces 14. The bowed portions 15 of the bars of the cross head receive the tubular shield and are 105 adapted to slide upward and downward thereon, the cross head being held against rotary movement by means of a screw 16, mounted in a threaded opening of one of the bowed portions 15 of the cross head and engaging a vertical longitudinal groove 17, 110 formed in the exterior of the tubular shield

1. The screw is also adapted to clamp the cross head to the shield, when it is desired to support the same and the pipe in an elevated position.
- 5 The dogs or catches 4 have rounded lower ends and are inclined upwardly and inwardly, being maintained in engagement with the tubular shield by means of springs 18. The blocks or pieces are provided with 10 curved seats 19 to support the lower rounded ends of the dogs or catches, which are secured to the cross head by bolts 20, piercing the side bars 13. The curved seats sustain the dogs or catches and relieve the bolts of 15 strain. The springs 18, which are curved, are secured by screws, or other suitable fastening means to the upper faces or edges of the blocks or pieces 14 at the inner ends thereof.
- 20 The lever 6 is preferably constructed of wood, the other parts of the apparatus being made of suitable metal, but a metallic lever may be employed if desired. The front engaging end of the lever is provided with a 25 recess 21 to enable it to fit around the tubular shield, and it is reinforced by a metallic plate or piece 22, secured by bolts 23 to the lever. The bolts also fasten a bottom plate 24 to the lower face of the operating lever.
- 30 The bottom plate 24 is provided with a plurality of integral depending ears 25, adapted to receive a pivot bolt 26 for connecting the lever to spaced sides 27 of a bracket 28, mounted on a block 29 and forming a fulcrum of the lever. The block 29 is preferably constructed of wood, and the bracket 28 is provided with a depending shank 30 embedded in the block, as shown. The fulcrum is shiftable or adjustable along the 35 lever to vary the relative lengths of the arms thereof to enable the lever to exert great power in withdrawing a pump pipe and also to be arranged for increasing the stroke of the lever and lifting the pipe when great 40 leverage is not required for pulling the same from the ground.
- In applying the apparatus to a pump pipe, the earth is dug from around the pipe to permit the tubular shield to be placed thereon. In pulling a pump pipe out of the 45 ground, the lever is operated to engage the catches with the top set of lugs, and the pipe is pulled the distance of one stroke of the lever. The catches are then engaged with the next set of lugs, and the pulling operation is repeated until the pipe has been lifted the length of the tubular shield. If this is insufficient to lift one of the sections of the 50 pump pipe clear of the ground, an extension section 31 is connected to the upper end of the shield 1 and to the cap 9, and the device is again operated to pull the pipe. The extension section 31 is threaded at its upper end 55 32 to screw into the cap, and it is equipped at its lower end with a coupling 33 to screw

on the upper end of the shield. As the extension tube 31 is applied to the upper end of the shield 1, the latter remains in position to co-act with the operating lever and consequently it is unnecessary to equip the extension tube with the lugs 3.

While only one tubular extension section is shown in the drawing, in practice the device will be equipped with sections of different lengths to enable it to be arranged to 75 suit the length of the sections of the pump pipe operated on.

Having thus fully described my invention, what I claim as new and desire to secure by Letters Patent, is:—

1. A device for pulling pump pipes including a tubular shield provided at intervals with lugs, means for detachably connecting the tubular shield to a pump pipe, a cross head movable along the tubular shield and provided with means for engaging the lugs thereof, and an operating lever for lifting the cross head.

2. A device for pulling pump pipes including a tubular shield adapted to be placed 90 on a pump pipe and provided at opposite sides with lugs arranged at intervals, means for detachably securing the shield to a pump pipe, a cross head having an opening to receive the shield and movable along the same, 95 catches mounted on the cross head at opposite sides of the shield and arranged to engage the lugs, and an operating lever provided with means for supporting the cross head at opposite sides of the shield and 100 adapted to be oscillated to lift the cross head.

3. A device for pulling pump pipes including a tubular shield adapted to be placed on a pump pipe, a cap provided with 105 threads for engaging the upper end of the pump pipe and having means for detachably engaging the upper end of the shield, a cross head slideable on the shield, means carried by the cross head for engaging the shield, and an operating lever engaged with and adapted to lift the cross head.

4. A device for pulling pump pipes including a tubular shield having a threaded upper end, a cap provided with a socket and having interior threads to screw on a pump pipe and on the shield, a tubular extension section having a threaded upper end and provided at its lower end with a coupling and adapted to form a continuation of 120 the tubular shield, a lever, and means carried by the lever for engaging the shield.

5. A device for pulling pump pipes including a tubular shield provided with a longitudinal groove, means for securing the shield to a pump pipe, a cross head movable along the shield and provided with a clamping screw operating in the groove and adapted to engage the shield, means carried 125 by the cross head for engaging the shield to 130

lift the same, and a lever having means for engaging the cross head at opposite sides thereof.

6. A device for pulling pump pipes including a tubular shield adapted to be placed on a pump pipe and provided with opposite lugs, means for detachably securing the shield to a pump pipe, a cross head composed of spaced bars, and blocks secured 10 between the terminal portions of the bars and provided with seats, the intermediate portions of the bars forming an opening to receive the tubular shield, spring actuated catches pivotally mounted at the seats and 15 arranged to engage the lugs of the shield, and a lever provided with means for engaging the cross head at opposite sides of the shield.

7. A device for pulling pump pipes including a shield adapted to be arranged on a pump pipe, means for securing the shield to a pump pipe, a cross head movable on the shield and provided with means for engaging the same, a lever having a forked 25 portion to straddle the shield and engage

the cross heads at opposite sides thereof, a forked metallic plate secured to the upper face of the lever, and means secured to the lower face of the lever for fulcruming the same.

8. A device for pulling pump pipes including a tubular shield, a cross head movable along the shield and having means for engaging the same, means for securing the shield to a pump pipe, a lever for lifting the 30 cross head, a plate secured to the lower face of the lever and provided with a plurality of ears, and an adjustable fulcrum comprising a block, a bracket having spaced sides to receive the ears of the lever and provided 35 with a shank embedded in the block, and a pivot detachably securing one of the ears of the lever between the sides of the bracket.

In testimony, that I claim the foregoing as my own, I have hereto affixed my signature in the presence of two witnesses.

PHILIP C. EMANUEL.
